UNITED STATES PATENT OFFICE.

LUCIUS DANA DRAPER, OF BOSTON, MASSACHUSETTS.

DESIGN FOR A PLATE FOR GARMENT-SUPPORTERS.

SPECIFICATION forming part of Design No. 28,467, dated April 12, 1898.

Application filed October 20, 1897. Serial No. 655,852. Term of patent 14 years.

To all whom it may concern:

Be it known that I, LUCIUS DANA DRAPER, a citizen of the United States, residing at Boston, in the county of Suffolk and State of Massachusetts, have invented and produced a new, useful, and original Design for a Plate for Garment-Supporters, of which the following is a specification, reference being had to the accompanying drawings, forming a part hereof, in which—

Figure 1 is a plan, Fig. 2 a section on line 2 2 of Fig. 1, and Fig. 3 a section on line 3 3 of Fig. 1, all enlarged for clearness and showing the body or plate of a garment-supporter 15 of my new design.

The leading or material feature of my design consists of an upper portion *a*, slotted at *a'*, merging into a bulbous portion *b*, curved below the slot *a* both crosswise and lengthwise, after the manner shown in the drawings.

What I claim is—

The design for the plate of a garment-supporter herein shown and described.

L. DANA DRAPER.
